G. F. WEISS.
SWITCH LOCKING DEVICE.
APPLICATION FILED JUNE 14, 1917.

1,282,339.

Patented Oct. 22, 1918.

UNITED STATES PATENT OFFICE.

GEORGE F. WEISS, OF SPRINGFIELD, ILLINOIS.

SWITCH-LOCKING DEVICE.

1,282,339.

Specification of Letters Patent. Patented Oct. 22, 1918.

Continuation of application filed October 14, 1916, Serial No. 125,532. This application filed June 14, 1917. Serial No. 174,658.

To all whom it may concern:

Be it known that I, GEORGE F. WEISS, a resident of Springfield, county of Sangamon, and State of Illinois, have invented 5 certain new and useful Improvements in Switch-Locking Devices, of which the following is a specification.

My invention relates to improvements in switch-locking mechanism, the principal objects being the provision of such a device which is simple and strong in construction, 10 efficient in operation, and inexpensive to maintain.

A further object of my invention is the provision of such a device including means connected to the movable tongue of a switch to operate a locking lever which engages a locking member, the latter being in the form of a double inclined faced or curved bar 20 pivoted at one end and resiliently held at the other, whereby the locking lever will be held on either side of the apex or summit of the curved bar against accidental movement, consequently holding and locking the tongue 25 of the switch in its adjusted position, until positively moved by the actuation of the usual operating means.

Another object of this invention is the provision of a simple and adjusting means 30 for attaching the box to the rail so as to securely hold it in position.

To the accomplishment of the foregoing and such other objects as may hereinafter appear, my invention consists in the construction, combination and arrangement of parts hereinafter described and then sought to be defined in the appended claims, reference being had to the accompanying drawing forming a part hereof and which shows 40 merely for the purpose of illustrative disclosure, a preferred embodiment of my invention, it being expressly understood that various changes may be made in practice within the scope of the claims without digressing from my inventive idea.

In the drawings,

Figure 1 is a top plan view of a device constructed according to my invention shown in position for use, the top plate or cover 50 being removed.

Fig. 2 is a transverse vertical cross-section on line 2—2 of Fig. 1;

Fig. 3 is a section on line 3—3 of Fig. 1;

Fig. 4 is a side elevation of the box, showing the means for attaching to the rail.

In the drawings, no means is shown for actuating or moving the tongue of the switch, as that forms no part of this invention, which is merely directed to the locking means for holding or locking the tongue in the position to which it is thrown.

The construction includes the casing 1, having a suitable top or cover and adapted to contain a suitable oil or other non-freezing material, in which the various operating parts are mounted. The casing may be secured to any standard form of rail having the elongated and slotted ear 2 at one end to receive a bolt or the like, and the elongated and flanged slot 3 along the inside to 65 slidably and adjustably receive the head of the securing bolt or other means, these bolts passing through suitable holes or apertures in the rail, the slots permitting the necessary adjustment of the casing, whereby a 70 simple and effective means of securing the casing to the rail is provided.

The casing 1 is apertured and provided with a stuffing box, as at 4, through which rod 5 passes. This rod is secured to the 75 tongue 6 of the switch by nuts 7 on each side thereof as shown in Figs. 1 and 2 and the stuffing box prevents leakage of the non-freezing fluid, the casing being air tight and filled with the fluid. This rod 5 is provided 80 on one end with the member 8 having an oblong recess 9 provided therein, in which fits the rounded head 9' on the short end of locking lever 10 which is pivoted on pin 11 connected to ear 12. This locking lever 10 has 85 its end bifurcated or forked as at 13 and has mounted therein the roller 14. This roller member bears on the locking member 15, the forked portion 13 of locking lever 10 extending on each side thereof. Locking 90 member 15 is pivoted as at 16 to one side of the casing and has its free end connected to the spring member 17; the other end of which is connected to an end wall of the casing. This locking member 15 is formed on a sort 95 of a double curve or incline leading to an apex or summit 18 and having a depression 19 near the free end thereof and another depression 19' near the other end thereof.

The locking lever 10 through the connections shown is adapted to be moved when the switch tongue is thrown and is moved on the locking member 15 accordingly, so that the roller in the forked portion is positioned on one side of the summit or apex 18, de- 100 105 110

pending on the position to which the tongue is thrown, the spring 17 being of sufficient strength to normally hold the locking member in position and prevent movement of the locking member 10 and consequently the tongue 6 of the switch is positively held or locked in position until sufficient force is applied to overcome the force of spring 17 and the leverage of locking lever 10.

10 The connection between the head 9' of the locking lever and the recess 9 in the member 8 is a loose connection, permitting relative movement between the parts as indicated in dotted lines. Cover plate 20 is 15 utilized to prevent leakage of oil or other non-freezing fluid in the casing.

This simple construction will effectively prevent accidental movement of the tongue of the switch, securely holding it against the 20 proper rail, and preventing accidental damage. It may be readily placed in position and secured to the rail, being embedded in cement or the like, with its top or cover exposed, so as to permit access for examination 25 or other purposes.

This application is filed as a continuation of my previous application, Serial Number 125,532, filed October 14th 1916.

What I claim is:—

30 1. A device of the character described including in combination, a rod adapted to be connected to a movable member of a switch, a locking lever operatively connected to said rod and having a bifurcated end portion, and 35 a locking lever formed with inclines leading to an apex or summit with which said bifurcated end portion of the locking lever engages so as to hold the movable member of the switch in its adjusted position.

40 2. A device of the character described including in combination, a rod adapted to be connected to a movable member of a switch, a locking lever operatively connected to said rod and having a bifurcated end portion, and 45 a locking lever formed with inclines leading to an apex or summit with which said bifurcated end portion of the locking lever engages so as to hold the movable member of the switch in its adjusted position, and a 50 spring connected to said locking member.

55 3. A device of the character described, including in combination, a casing having an elongated and flanged slot on one side and a slotted ear on one end adapted to adjustably receive the securing members, a rod adapted to be connected to the movable member of a switch, and a locking lever operatively connected to said rod and a locking member with which the locking lever 60 operates so as to hold the movable member of the switch in its adjusted position.

65 4. A device of the character described, including in combination, a casing adapted to contain a non-freezing fluid having a cover and means for securing said casing to a rail

adjacent a switch, a locking member pivotally mounted within the casing and having a spring connected to its free end, said locking member formed with inclines leading to a summit, a lever member pivotally mounted within the casing and bearing against the inclines of said locking member, and a rod for operating said lever member connected to the movable member of the switch, said casing being provided with a stuffing box to 75 permit the passage of the rod therethrough.

5. A device of the character described, including in combination, a rod adapted to be connected to a movable member of a switch, said rod having a member on the end provided with an enlarged recess, a locking lever pivotally mounted and having an enlarged head loosely fitting in said recess, said locking lever having a bifurcated end portion, and a locking member formed with 85 inclines leading to an apex or summit with which said bifurcated end portion of the locking lever engages so as to hold the movable member of the switch in its adjusted position.

6. A device of the character described, including in combination, a casing, a rod extending thereinto adapted to be connected to the movable member of a switch, said rod having a member on the end thereof inside 95 of said casing provided with an enlarged recess, a lever member pivotally mounted within the casing and having an enlarged head loosely fitting in said recess, a locking member having one end pivotally connected to 100 said casing and a spring connected to the free end of the locking member and said casing, said locking member being formed with inclines leading to an apex or summit, said lever member having its end bifurcated with 105 a roller member therein adapted to engage said locking member.

7. A device of the character described including in combination, a casing adapted to contain a non-freezing fluid having a cover 110 and means for securing said casing to a rail adjacent a switch, a locking member pivotally mounted within the casing and having a spring connected to its free end, said locking member formed with inclines leading to 115 a summit, a lever member pivotally mounted within the casing and bearing against the inclines of said locking member, said lever having an enlarged head on its shorter end, a member provided with an enlarged recess in 120 which said head loosely fits, slidably mounted within the casing, and a rod for actuating said member and secured to the movable member of a switch, said casing being provided with a stuffing-box to permit the passage of the rod therethrough.

8. A device of the character described, including in combination, a casing having an elongated and flanged slot along one side and a slotted ear on the same side adapted 125

to adjustably receive the securing members which are to be attached to the rail, a rod adapted to be connected to the movable member of a switch, a rocking lever operatively connected to said rod and a locking member with which said locking lever cooperates so as to hold the movable member of the switch in its adjusted position.

9. A device of the character described, including in combination, a casing having an elongated and flanged slot on one side and a slotted ear on one end adapted to adjustably receive the securing members, a rod passing out of the casing and adapted to be connected to the movable member of a

switch, and means within the casing adapted to hold the movable member of the switch in its adjusted position.

10. A device of the character described, including in combination, a casing having an elongated and flanged slot along one side and a slotted ear on the same side adapted to adjustably receive the securing means which are to be attached to the rail, a rod extending out of the casing and adapted to be connected to the movable member of a switch, and means within the casing adapted to hold the movable member of the switch in its adjusted position.

GEORGE F. WEISS.
